His Attorney.

UNITED STATES PATENT OFFICE

2,017,702

REFRIGERATOR CABINET

Delbert F. Newman, Schenectady, N. Y., assignor
to General Electric Company, a corporation of
New York

Application June 8, 1934, Serial No. 729,622

3 Claims. (Cl. 220—9)

My invention relates to refrigerator cabinets, and particularly to door frame constructions for such cabinets.

In constructing refrigerator cabinets it is desirable that the admission of moist air to the space containing heat insulation between the inner and outer walls be prevented, in order to avoid the condensation of moisture on the inner wall which is cooled by the refrigerating unit. Such condensation of moisture deteriorates the insulation and, for this reason, it is desirable to construct all the wall joints such as those around the door frame so as to seal the space between the inner and outer walls and to prevent admission of air to the insulation.

It is an object of my invention to provide a refrigerator cabinet having an improved door frame, which may be readily attached in such manner as to seal the joint between the door frame and the cabinet walls.

Further objects and advantages of my invention will become apparent as the following description proceeds, and the features of novelty which characterize my invention will be pointed out with particularity in the claims annexed to and forming a part of this specification.

For a better understanding of my invention reference may be had to the accompanying drawing in which Fig. 1 is an elevation partly in section of the top of a refrigerator cabinet embodying my invention, and Fig. 2 is an enlarged detail sectional view of the insulated door frame shown in Fig. 1.

Referring now to Fig. 1, I have shown a refrigerator cabinet 10 comprising inner and outer metal walls 11 and 12 respectively and a body of insulation 13 filling the space between the walls. The walls 11 and 12 terminate about a door opening which is provided with a unitary frame 14 comprising four integral strips of molded hard rubber or other suitable moisture impervious material of low heat conductivity such as a resinous condensation product. A door 15 hinged to the cabinet at 16 is provided to close the door opening. A gasket 17 secured about the under edge of the rim of the door seals the door opening when the door is closed.

In accordance with my invention, a sealed joint is provided between the door frame 14 and the wall of the cabinet. As clearly shown in Fig. 2, the joint between the inner metal wall of the cabinet and the frame 14 includes a roll or bead 18 along the upper end of the inner wall 11 and a groove 19 conforming to the bead, in the frame 14 which extends around the lower edge thereof,

and fits closely over the bead 18. The wall 11 and frame 14 are clamped together by bridging members 20 and screws 21 threaded within bosses 22 formed at intervals around the outside of the frame 14. In order to press the bead 18 firmly into the groove 19 in the frame 14, the bridging members 20 are bent to provide portions 23 extending into the bead 18 and the outer edges of the bridging members rest on projections 24 formed on the bosses 22. It is apparent that when the screws 21 are tightened the portions 23 of the lugs will force the bead 18 into the groove 19 and thereby clamp together the wall 11 and the frame 14. In order to secure the frame 14 to the portion of the outer wall 12 extending over the upper side of the frame, a shoulder 25 is provided about the upper edge of the frame and a flange 26 on the wall 12 is turned down over the shoulder 25. A plurality of screws 27 threaded into the upper ends of the bosses 22 secure the wall 12 to the frame 14. These joints between the frame and the walls 11 and 12 may be tightened with sufficient pressure to seal the joints against admission of air due to changes of temperature in the insulation space between the walls. However, I may use a cement between the frame and the walls to insure a more positive seal. It is apparent from the foregoing that the walls 11 and 12 are securely fastened and sealed to the frame 14 and that the entire construction is simple and rugged.

While I have shown my invention as applied to a refrigerator cabinet, I do not desire my invention to be limited to the specific construction shown and described, and I intend in the appended claims to cover all modifications within the spirit and scope of my invention.

What I claim as new and desire to secure by Letters Patent of the United States, is:

1. A refrigerator cabinet having a door opening and comprising spaced inner and outer metallic walls, heat insulating material between said walls, a bead formed on one of said walls about said door opening, a strip of moisture impervious material of low heat conductivity arranged between said walls about said door opening and having a groove engaging said bead, and means including a bridging member secured to said strip and having a portion thereof engaging said bead for securing said strip to said one wall and for clamping said bead in said groove.

2. A refrigerator cabinet having a door opening and comprising spaced inner and outer metallic walls, heat insulating material between said walls, a bead formed in one of said walls about said door

opening, a unitary frame of moisture impervious material and of low heat conductivity connecting said walls about said door opening and having a groove engaging said bead, and means including a bridging member secured to said frame and having a portion thereof engaging said bead for securing said frame to said one wall and for clamping said bead in said groove.

3. A refrigerator cabinet having a door opening and comprising spaced inner and outer metallic walls, heat insulating material between said walls, a bead formed on one of said walls about

said door opening, a unitary frame of moisture impervious material and of low heat conductivity extending between said walls and about said door opening and having a groove engaging said bead, a plurality of bosses on said frame, and means including a bridging member secured to each of said bosses and having a portion engaging said bead and another portion engaging said boss for securing said frame to said one wall and for clamping said bead in said groove. 10
